UNITED STATES PATENT OFFICE.

BENJAMIN B. ENGLANDER, OF BROOKLYN, NEW YORK, ASSIGNOR TO THE ENGLANDER SPRING BED COMPANY, OF BROOKLYN, NEW YORK, A CORPORATION OF NEW YORK.

HAMMOCK.

Application filed December 7, 1920. Serial No. 428,900.

To all whom it may concern:

Be it known that I, BENJAMIN B. ENGLANDER, a citizen of the United States, residing at Brooklyn, in the county of Kings and State of New York, have invented certain new and useful Improvements in Hammocks, of which the following is a specification.

This invention relates to hammocks of that general class known as couch hammocks, the object of the invention being to provide an improved hammock having an improved adjustable and detachable back, and also improved means for supporting the hammock.

In the present improvement the back is a framed back, that is, the framework of the back is of rigid construction for supporting a suitable fabric such as a spring fabric, and this back is connected with the seat in such manner that it not only may be adjusted in various angular positions relatively to the seat but may be freely detachable therefrom and also foldable upon the seat when desired.

In the drawings accompanying and forming a part of this specification, Fig. 1, illustrates a perspective view of this hammock, supported by suitable up-rights; Fig. 2, is an end view of the hammock; Fig. 3 is a detail perspective view of the back adjustable means; and Fig. 4 is a detail view of the means for supporting the back at its lower edge.

Similar characters of reference indicate corresponding parts in the several figures of the drawings.

This improved hammock comprises a bottom or frame, 2, preferably comprising a metal spring upon which rests a stuffed mattress or seat 3. The frame of the metal spring comprises a pair of angle iron ends or cross-bars, 4, connected by suitable lengthwise extending bars. Secured to these cross-bars in any suitable way, is a pair of fabric ends, 5, each having at its upper end a spreader bar 6. The spreader bar in the present form of hammock, is connected to the angle bars of the seat by a pair of cables such as chains, 7, the lower ends of which are secured to the angle iron cross-bars while the upper ends are fastened by means of hooks to the spreader bar. The spreader bar in the present instance has secured thereto, preferably by

means of hooks, a pair of coiled springs, 8, and these coiled springs are attached at their upper ends to the supporting cables or chains 9, by means of which the hammock is suspended by any suitable supporting means. By this means of support the weight on the hammock is carried by the supporting chains and not by the fabric ends, so that these may be made of thin material, such as cretonne without imparting any strain thereto which would quickly tear such a fabric. In other words the weight of the hammock is carried by the supporting chains and not by the fabric ends, which latter would not be sufficiently strong, especially when, as is very frequently the case, thin materials are used for this purpose.

The back also comprises an angle iron framework, consisting of two lengthwise extending angle iron bars, 9' and 10, connected by a pair of upright bars, 11, to which is connected any suitable fabric 12. The lower bar 10, is provided with a pair of bent metal members 13 in position to be inserted into a pair of openings, 14, located in the rear angle bar, 15, of the seat, in such manner that the back can swing or be adjusted toward and from the hammock or be swung down upon the seat framework upon removing the cushions or stuffed seat, the openings and irons forming as it were, a detachable hinge whereby the back, by proper manipulation can be detached, this being accomplished by bringing the back into substantial parallelism with the seat, it not being possible, however, to detach it while in a perpendicular position. Thus it cannot become prematurely unfastened while the user is leaning against the same. In the present instance the bent portions of the irons extend forward or toward the front of the hammock, thus requiring the back to be bent over upon the seat in order to detach it and thus the weight of the back is supported by the seat during this operation. Consequently the back cannot, as herein-after stated, be detached while in a perpendicular position, nor can it be prematurely folded forward so as to be detached until the seat cushions have been removed. Consequently the premature detachment of the back is not possible in any way while the hammock is in use. At the rear end of

each spreader bar and at each upper corner of the back, is a hook and a short chain, one secured to the spreader bar and the other to the back, and the links of the chain 5 may be hooked into the hooks of the spreader bar, whereby the back may be adjusted into different positions as the chain is lengthened or shortened.

It will be observed that in the present improvement, the chains 9 are connected with the spreader bars at the same, as at the inner, sides of the chains 7, which latter run in parallelism from the spreader bars to the seat bars, and at the outside of the fabric 10 ends, so that they are out of the way and do not interfere with the comfort of the user when leaning against the fabric ends of the hammock. Thus in the present improvement it will be seen that I have provided a couch 15 bed hammock having a framed seat and a framed back, the latter freely connected with the seat by the insertion of a part of one into a part of the other and which connection is such that the back may not only be 20 adjusted into various angular positions relatively to the seat but may also be foldable upon the seat and also readily detachable from the seat, and that in the present instance the connection between the framed seat 25 and the framed back is obtained by the provision of simple openings and bent irons which thus permits the back to be folded, to be adjusted and readily detached by merely folding the back upon the seat and with- 30 drawing the irons from the openings. By this construction the necessity of handling a framed back and seat permanently united together is avoided since the back may be 35 readily detached and handled alone and consequently the seat may be handled alone. It will also be observed that the adjustment of the back into various angular positions is obtained by flexible connecting means be- 40 tween the back and the spreader bars at the ends of the hammock, and I believe that I am the first to provide a swinging couch 45 hammock having a rigid framed back adjustable into various angular positions relatively to the seat and which is also detachable and foldable.

From the foregoing it will be seen that the back of applicant's hammock is connected with the seat along the rear edge thereof, so that it may be adjusted to the rear of the hammock into various inclined positions, and consequently its hinged connection with the seat of the hammock along

the rear edge thereof does not in any of such adjusted positions take up any of the space of the seat while at the same time it can 60 be folded forward upon the seat when it is desired to detach it.

The various details may be more or less changed without departing from the spirit or scope of the present improvement. 65

I claim as my invention:

1. In a couch hammock, the combination of a couch bottom comprising a fabric connected frame, a pair of wind shield end members connected to said frame, and a fabric 70 connected framed back connected to said couch bottom frame and end members, the connections thereof with the bottom frame comprising a plurality of pairs of slots and bent projections insertable into said slots, 75 one of each pair carried by the bottom frame along one side thereof and the other by the back along one longitudinal edge thereof for permitting the back to be readily detached and assembled with the structure. 80

2. In a couch hammock, the combination of a couch bottom comprising a fabric connected frame, a pair of wind shield end members connected to said frame and having spreader bars at their upper ends, a fabric 85 connected framed back connected to said couch bottom frame and end members, the connections comprising means for permitting the back to be readily detached and assembled with the structure and consisting 90 of a plurality of pairs of slots and projecting bent members, one of each pair carried by the bottom and the other by the back, and means for adjustably and detachably connecting the back directly with the 95 spreader bars.

3. A couch hammock comprising a seat having a pair of transverse bars, a pair of fabric wind shield ends secured thereto having spreader bars at their upper edges, chains connecting the spreader bars with the seat bars and located at the outside of the fabric ends, and chains having coiled springs in their length and connected with the spreader bars for supporting the hammock, an adjustable back detachably connected with the seat and detachable therefrom only when the back is in a substantially horizontal position, and flexible means connecting the back with the spreader bars for adjusting the back at various angles relatively to the seat. 100

Signed at Brooklyn, Kings County, New York, this 30th day of November, 1920.

BENJAMIN B. ENGLANDER.
